UNITED STATES PATENT OFFICE.

WILLIAM DENT PRIESTMAN, SAMUEL PRIESTMAN, AND HAROLD RICHARDSON, OF HULL, ENGLAND.

IGNITER FOR HYDROCARBURETED-AIR ENGINES.

SPECIFICATION forming part of Letters Patent No. 614,889, dated November 29, 1898.

Application filed December 20, 1897. Serial No. 662,680. (No model.)

To all whom it may concern:

Be it known that we, WILLIAM DENT PRIESTMAN and SAMUEL PRIESTMAN, of Holderness Foundry, and HAROLD RICHARDSON, 5 of 57 Walmsley street, all of the town and county of Kingston-upon-Hull, England, subjects of Her Majesty the Queen of Great Britain and Ireland, have invented new and useful improved means applicable for use in 10 igniting the working charge in hydrocarbureted-air engines, (in respect whereof we have obtained Letters Patent in Great Britain, No. 6,738, dated March 27, 1896, and in respect whereof we have applied for Letters 15 Patent in Great Britain, No. 24,457, to bear date November 2, 1896,) of which the following is a specification.

This invention relates to motor-engines operated by the combustion of hydrocarbon vapors mixed with air; and it consists in an improved method of and apparatus for igniting the working charge.

The accompanying drawings represent our improvements applied, by way of example, to 25 a hydrocarbureted-air engine of the double-cylinder vertical type, Figure 1 being a side view, and Fig. 2 a face view, of so much of the engine as is necessary to illustrate the present invention.

30 In carrying out this invention a tube A, to the interior of which the inflammable charge has access, is arranged across the chimney B of a heating-lamp C. The tube A is open at one end to the motor-cylinder or combustion-chamber D (a lamp and tube being provided for each cylinder in the case illustrated) and is provided at its opposite or outer end with an air-admission valve D'.

We have found that in order to insure the 40 best effect the lower portion of the chimney which incloses the heating-tube should assume the form of a hollow truncated cone, having its larger diameter at the base. After diminishing in diameter for some distance 45 above the heating-tube the chimney again expands and may finally terminate in a parallel portion, as shown at B'. In this section is arranged a loose perforated baffle-plate b, the object being to retain the heat in the tube 50 and so maintain it at a sufficiently high temperature. With the same object the upper

extremity of the chimney is closed by a loose perforated cover b', the released vapor from the igniting-tube entering during the compression stroke the upper portion of the 55 chimney and being there consumed. Surrounding that portion of the conical part which incloses the heating-tube is a casing or wind-shield b², arranged to rotate and provided with a hole b³ about the level of the 60 heating-tube. The conical portion of the chimney is also formed with a hole at the same level, the two holes when brought opposite one another being so disposed and of such a size as to permit of the inclosed parts 65 being readily cleaned.

In mounting the heating-tube in the motor-cylinder or combustion-chamber and across the lamp-chimney we form the inner extremity of the said tube with a collar, which fits 70 a recess in the face of a plug which is screwed into the cylinder, or a distance-piece may be introduced between the collar and the plug, as illustrated in the present design, the neck of the distance-piece being provided with a 75 cock for controlling the passage of the working charge to and from the heating-tube.

a is the collar upon the extremity of the heating-tube.

d is the plug for screwing to the cylinder, 80 packing, consisting of layers of asbestos and iron, being employed to prevent the radiation of heat to the cylinder.

e is the distance-piece, fitted with a plug e'. The side of the chimney is formed with a flange 85 b⁴, adapted for being bolted to the flange e² or to the plug d, as the case may be, thus securing the heating-tube in position gas-tight. Portions of the chimney are furnished with asbestos linings to protect them from the effects of excessive heat. The movements of 90 the valve D' are controlled by suitably-timed mechanism, regulated in such a manner that a small portion of the charge is allowed to escape while compression of the charge in the cylinder is taking place or until the crank 95 has arrived at or beyond the dead-center. While the air-valve remains open the charge is not ignited and preignition is guarded against, the vapor not being capable of ignition until arrested in its passage through the tube. So soon as the valve closes, however,

ignition and combustion ensue. The portion of the compressed charge allowed to escape also operates as a scavenging charge.

In the drawings annexed the valves D' are opened and closed by means of a lever f, having its fulcrum at f', the lever being operated from a convenient moving part of the engine through the intervention of a connecting-rod, such as g, and arm g'.

10 In order to regulate the timing of the valve or valves D', so as to render the ignition of the charge earlier or later, we provide adjusting-screws h and thumb-nuts h', the former h of which screw through bosses f² f² on the 15 lever f. By thus regulating the timing of the air-valve in starting premature ignition of the charge and reversal of the engine are avoided.

For the purpose of holding open the valve 20 D' of one of the igniters in a double-cylinder engine we provide a distance-piece or wedge i, same being conveniently connected to the engine by means of a chain i'. At the time of starting the engine this wedge is inserted 25 between the lower extremity of the valve-stem D² of one of the air-valves and the upper extremity of the adjusting-screw h, pertaining thereto, its function being to hold the valve open until the piston has effected a 30 small portion of its stroke by reason of the compressed air which passes into the cylinder before the valve closes. The wedge becomes displaced almost immediately the piston moves, the valve closes, and the charge is 35 fired, whereby impulse is given to the piston.

By these means the set-screw h may be retained in its correct position for the next impulse stroke, whereas if the wedge were not used and the set-screw h set for holding the valve open at starting the valve would remain open for a longer period than is desirable—i. e., too late in the following cycle of the piston.

What we claim as our invention, and desire to secure by Letters Patent, is—

1. The improved igniting device comprising a tube A, open at one end to the motor-cylinder or combustion-chamber and arranged across the chimney B of the heating-lamp C, the portion of the said chimney inclosing the 50 tube being formed as a truncated cone having its larger diameter below and its smaller diameter above the level of the said tube; the said portion of smaller diameter communicating with an expanded chamber B' wherein is 55 a perforated baffle-plate and whereon is fitted a perforated cover-plate, substantially as and for the purposes specified.

2. In a hydrocarbureted-air engine, the combination, with a motor-cylinder, of a heating-tube A, chimney B B', baffle-plate b, cover-plate b', heating-lamp C, air-admission valve D', lever f and thumb-screws h h', substantially as and for the purposes set forth.

WILLIAM DENT PRIESTMAN.
